UNITED STATES PATENT OFFICE.

GEORGE A. EDE, OF COBDEN, ILLINOIS.

CLUTCH.

SPECIFICATION forming part of Letters Patent No. 732,402, dated June 30, 1903.

Application filed March 16, 1903. Serial No. 148,131. (No model.)

To all whom it may concern:

Be it known that I, GEORGE A. EDE, a citizen of the United States, residing at Cobden, in the county of Union and State of Illinois, have invented certain new and useful Improvements in Clutches, of which the following is a full, clear, and exact description, reference being had to the accompanying drawings, forming part of this specification.

10 My invention relates to a clutch for intermittently rotating a shaft upon which it is mounted.

The invention consists in features of novelty hereinafter fully described, and pointed out in the claims.

Figure I is a perspective view of my clutch with the engaging pulley omitted. Fig. II is a perspective view of the clutch engaging pulley. Fig. III is a view, partly in elevation and 20 partly in section, of the retaining-yoke of the clutch. Fig. IV is a horizontal section taken on line IV' IV', Fig. III. Fig. V is a vertical section of the clutch. Fig. VI is a perspective view of the stop-block which receives the 25 slide-bolt in the clutch-collar. Fig. VII is a perspective view of the slide-bolt.

1 1 designates a support in which a driven shaft 2 is rotatably mounted. The shaft 2 is provided with a keyway 3.

30 4 designates a retaining-yoke that has connected to it a pull-rod 5, which may be actuated in any suitable manner. The retaining-yoke 4 is provided with an elongated aperture 6, through which the driven shaft 2 passes 35 and which renders vertical movement of the yoke with respect to the driven shaft possible. In order to prevent lateral movement of the yoke 4 and wear of the yoke upon the driven shaft, I provide a lug 7, (see Figs. III and IV,) 40 which projects from the rear face of the yoke and seats in a socket 8 in the support 1, so as to rest at the bottom of said socket when the retaining-yoke is in lowered position and uphold said yoke from contact with the driven 45 shaft, as seen in Fig. III.

9 is a stop-block secured to the upper end of the retaining-yoke 4 and having its lower end projected downwardly clear of the retaining-plate and furnished with an inclined face 50 10. (See Figs. IV and VI.) The forward face

of the retaining-yoke is provided with a recess 11, and located beside said recess is a vertical hardened plate 12. (See Figs. III and IV.)

13 designates a pulley loosely mounted on the driven shaft 2, the hub of which is provided with an annular flange 14.

15 designates dogs set into the hub of the pulley 13 (see Figs. II and V) and projecting into the space within the annular flange 14.

16 is a clutch-collar fixed to the driven 60 shaft 2 by a key 17, (see Fig. I,) fitting in the keyway 3 of said shaft, and also by a set-screw 18. (See Fig. V.) Slidably positioned in the clutch-collar 16 is a bolt 19, the outer end of which is adapted to be projected toward the loose pulley 13 to be engaged by the dogs 15. This slide-bolt is provided at its inner end with a laterally-extending arm 20, that protrudes through a slot 21 in the perimeter of the clutch-collar.

22 (see Fig. V) is an expansion-spring located within the clutch-collar and adapted to bear against a finger 23, carried by the slide-bolt 19, for the purpose of projecting said slide-bolt in an outward direction when the 75 bolt is free from the restraining means by which it is held inwardly, in a manner to be hereinafter set forth in connection with the operation of the clutch.

When in the practical use of the clutch the 80 shaft 2 is being driven thereby, the retaining-yoke 4 is in elevated position, as seen in dotted lines in Fig. V, and the slide-bolt 19 is held in projected position, as seen in dotted lines, by the spring 22 bearing thereagainst. 85 It will be seen that with the parts in the position stated the loose pulley 13 continually engages the clutch-collar through the medium of one of its dogs 15 and that the shaft will 90 be driven as long as the parts remain in such positions. When it is desired to throw the clutch-collar out of engagement with the loose pulley, the retaining-yoke 4 is lowered into the position seen in Figs. I, III, and V, thereby moving the lower end of the stop-bolt 9 downwardly to the perimeter of the clutch-collar. The result is that the projecting arm 20 of the slide-bolt 19 engages the inclined face 10 of the stop-block and moves the slide-bolt inwardly into the position shown in full lines, 95 100

Fig. V, thereby withdrawing the outer end of the bolt from engagement with the previously engaging dog 15, thereby permitting rotation of the loose pulley freely on the shaft 2 without imparting movement thereto.

For the purpose of preventing sudden jar of the driven shaft and its clutch I provide a cushion-pin 24. (See Figs. III and IV and dotted lines, Fig. V.) This cushion-pin is 10 slidably positioned in a barrel 25, extending horizontally from the retaining-yoke 4 and containing a spring 26, located in the rear of said pin. The forward end of the pin projects into a position in the rear of the lower 15 end of the stop-block 9, so that when the projecting arm 20 of the slide-bolt 19 passes into the rear of said stop-block it will strike said cushion-pin and be cushioned in its stoppage. In order to prevent retrograde rotation of the 20 clutch-collar when the cushion-pin 24 is engaged, I provide a stop-pin 27, seated in the clutch-collar and backed by an expansion-spring 28. The outer end of this stop-pin projects beyond the end face of the clutch-25 collar opposing the retaining-yoke 4, and when the slide-bolt arm 20 reaches the cushion-pin 24 the stop-pin passes the stop-plate 12 on the face of the retaining-yoke and enters the recess 11 in said yoke, as seen in Fig. IV and 30 dotted lines, Fig. III, where it serves to hold the clutch-collar from retrograde movement.

I claim as my invention—

1. In a clutch, the combination with a shaft, of a collar mounted on said shaft, a slotted 35 retaining-yoke located alongside of said collar, and loosely fitted to said shaft for sliding movement thereon, a slide-bolt in said collar for engagement with said retaining-yoke, and a loose pulley having means for engaging said 40 slide-bolt, substantially as set forth.

2. In a clutch, the combination with a shaft, of a collar mounted on said shaft, a slotted retaining-yoke located alongside of said collar and loosely fitted to said shaft for sliding 45 movement thereon, a slide-bolt in said collar for engagement with said retaining-yoke, a loose pulley, and a dog carried by said pulley for engagement with said slide-bolt, substantially as set forth.

3. In a clutch, the combination with a shaft, of a collar mounted on said shaft, a slide-bolt in said collar, a slotted retaining yoke or member located alongside of said collar, and loosely fitted to said shaft for sliding movement 50 thereon, a slide-bolt, and a loose pulley.

ley having means for engaging said slide-bolt, substantially as set forth.

4. In a clutch, the combination with a shaft, of a collar mounted on said shaft, a spring-pressed slide-bolt located in said collar and 60 having an arm protruding through the perimeter of the collar, a slotted retaining member located alongside of said collar and loosely fitted to said shaft for sliding movement thereon, and a stop-block carried by said retaining member to be engaged by the arm of said slide-bolt, substantially as set forth.

5. In a clutch, the combination with a shaft, of a clutch-collar mounted on said shaft, a slide-bolt located in said collar and having an 70 arm projecting through the perimeter of the collar, a slotted retaining member located alongside of said collar and loosely fitted to said shaft for sliding movement thereon, and a stop-block having a lower inclined end to 75 be engaged by the arm of said slide-bolt, substantially as set forth.

6. In a clutch, the combination of a shaft, a collar mounted on said shaft, a support for said shaft, a slotted retaining member located 80 alongside of said collar, and loosely fitted to said shaft for sliding movement thereon, and a lug carried by said retaining member to engage said support to limit the movement of said retaining member, substantially as set forth. 85

7. In a clutch, the combination with a shaft, of a collar mounted on said shaft, a spring-pressed slide-bolt located in said collar and having an arm projecting therefrom, a retaining member located alongside of said collar, 90 a stop carried by said retaining member, and a cushion-pin to receive the arm of said slide-bolt when it is engaged by said stop, substantially as set forth.

8. In a clutch, the combination with a shaft, of a collar mounted on said shaft, a spring-pressed slide-bolt located in said collar and having an arm projecting therefrom, a retaining member, a stop carried by said retaining member to be engaged by said slide-arm, and a stop-pin carried by said collar to engage 100 said retaining member when said slide-bolt arm engages said stop, substantially as set forth.

In testimony whereof I have hereunto set 105 my hand this 7th day of March, 1903.

GEORGE A. EDE.

In presence of—

JOHN McCAFFREY,
R. L. RICH.
